F. SOLEY

LATCH LOCK

Filed Jan. 10, 1923

Inventor:
Frank Soley
By his Attorneys
Hawkins & Brornick

UNITED STATES PATENT OFFICE.

FRANK SOLEY, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

LATCH LOCK.

Application filed January 10, 1923. Serial No. 611,772.

To all whom it may concern:

Be it known that I, FRANK SOLEY, a citizen of the United States, residing in Philadelphia, Pennsylvania, have invented certain 5 improvements in Latch Locks, of which the following is a specification.

The object of my invention is to improve the construction of latch locks by providing a tumbler that will lock the bolt in the projected position when it is moved by turning the key a given distance, and which will be moved clear of the bolt when the key is turned fully to withdraw the bolt. When the tumbler is in the last mentioned position, 10 the bolt becomes a spring latch that can be operated independently of the key by retracting a pin projecting through a slot in the cover plate of the lock.

The invention is especially adapted for use as a locker lock when it is desired to arrange the locking mechanism so that the bolts can be retracted without the use of a key, and which can be locked by turning the key to a given position.

25 In the accompanying drawings:

Fig. 1 is a perspective view of my improved latch lock;

Fig. 2 is a view of the lock with the cap plate removed, showing the tumbler locking the bolt in the projected position;

Fig. 3 is a view, similar to Fig. 2, showing the tumbler raised free of the bolt, allowing the bolt to be used as a latch;

Fig. 4 is a sectional plan view on the line 35 4—4, Fig. 2;

Fig. 5 is a transverse sectional view on the line 5—5, Fig. 2; and

40 Figs. 6 to 9, both inclusive, are detached perspective views of parts of the lock.

Referring to the drawings, 1 is the casing of the lock, which is made of sheet metal in the present instance. 2 is the cover plate, which is secured in position in the ordinary manner. 3 and 4 are studs projecting into the casing. 5 is a sliding bolt, beveled at the outer end, as shown in Fig. 6. This bolt has a rear slot 6 through which the stud 4 extends, and a forward slot 7 communicating with a recess 8 in the lower edge of the bolt. 45 The rear wall of the recess is shaped to be engaged by a key so that, on turning the key in one direction, the bolt can be retracted. A spring 9 acts to project the bolt. This spring is mounted on a post 10. One arm

of the spring rests against a lug 11 on the bolt and the other arm rests against the wall of the casing.

12 designates a key hub made as shown in Fig. 9 and slotted for the reception of a flat key. 13 designates a tumbler (Fig. 7) 60 having a slot 14 at its forward end for the stud 3, on which it is pivoted. A heel 15 at its rear end, which, when the tumbler is in the position shown in Fig. 2, rests against the stud 4, which acts as a fixed stop. On 65 the upper edge of the tumbler is a lateral projection 16 that extends over the upper edge of the bolt. When the tumbler is in the position shown in Fig. 2, the projection 16 rests back of a shoulder 17 on the bolt, 70 preventing the withdrawal of the bolt. When the tumbler is raised and is moved back by the key, it rests on the top of the stud 4, which holds the projection 16 clear 75 of the bolt. A spring 18, mounted on the post 10, has one arm that rests against the upper edge of the tumbler 13, and another arm that rests against the wall of the casing, as shown in Fig. 2. This spring holds the tumbler in either of its two positions. 80

Projecting from the lower edge of the tumbler in advance of the key hub is an extension 19 that is in the path of the key when the tumbler is in the retracted position, Fig. 3. When the key is turned to engage the extension 19, it moves the tumbler forward, and the spring 18 forces the tumbler in front of the stud 4, which acts as a stop, and, as the bolt is in the projected position, the projection 16 rests back of the shoulder 17, holding the bolt against movement until the key is turned to raise the tumbler clear of the stud 4 and force it back so that it rests on the stud, the bolt, in the meantime being withdrawn by the key. 95

On the bolt 5 is a pin 20, which projects through a slot 21 in the cover plate 2. The bolt can be withdrawn by manipulating the pin without using the key, when the parts are in the position shown in Fig. 3. 100

On the stud 3 are two disks, which form wards, the key being cut to receive the wards. It will be understood that key changes can be made by shifting the wards, or by changing their diameters, and that a single ward 105 may be used, or a series of wards, depending upon the lock. While the wards are shown in the form of disks, other wards may be

used without departing from the main features of the invention.

I claim:

1. The combination in a lock, of a casing having two studs; a bolt arranged to slide on said studs; a tumbler arranged to slide on one stud and to rest in front of the other stud, or on top of the said other stud, the tumbler engaging the bolt when in the first mentioned position to lock it against movement; a key; and means, independent of the key, for retracting the bolt.

2. The combination in a lock, of a casing having two studs; a bolt arranged to slide in the casing; a tumbler arranged to slide on one stud and to rest in front of the other stud, or on top of the latter stud, the tumbler having a projection arranged to engage the bolt when the tumbler is in the first mentioned position; and means, independent of the key, for retracting the bolt.

3. The combination in a lock, of a casing; a bolt arranged to slide in the casing; a stud on the casing; a tumbler arranged to slide and turn on the stud and to engage the bolt when in its forward position; and a fixed stop on the casing to hold the tumbler against rearward movement when said tumbler is in the forward position, the tumbler being raised clear of the bolt and the fixed stop when actuated by a key, said bolt hav-

ing means by which it can be retracted without a key.

4. The combination in a lock, of a casing; a bolt arranged to slide in the casing; two studs in the casing; a slotted tumbler arranged to slide on one stud and to rest upon, or in front of, the other stud, said tumbler being shaped to be engaged by a key to move it forward, or to raise and retract it; a spring tending to hold the tumbler yieldingly; a spring for projecting the bolt; and an operating pin on the bolt, the casing being slotted for the passage of the pin.

5. The combination of a casing; a slotted cap plate; a key hub; a sliding bolt having two slots therein; two studs projecting from the casing and through the slots in the bolt; a lug and an operating pin on the bolt, the pin extending through the slot in the cap plate; a slotted tumbler mounted on the forward stud and having a projection arranged to drop back of the lug on the bolt and also having a forward extension, the tumbler being shaped to be engaged by a key in the key hub which raises and retracts it; a spring for projecting the bolt; a spring resting on the upper edge of the tumbler to hold it yieldingly in position; and a ward on one of the studs.

FRANK SOLEY.
